CORPORATION OF NEW YORK.

REED TELEPHONE RECEIVING.

Application filed November 19, 1920. Serial No. 425,058.

To all whom it may concern:

Be it known that I, GREENLEAF WHITTIER PICKARD, a citizen of the United States of America, and a resident of Newton Center, 5 State of Massachusetts, have invented certain new and useful Improvements in Reed Telephone Receiving, the principles of which are set forth in the following specification and accompanying drawings, which 10 disclose the form of the invention which I now consider to be the best of the various forms in which the principles of the invention may be embodied.

This invention relates to electromagnetic 15 reed telephone receiving for use in either radio or wire communication of either telephonic or telegraphic intelligence, and especially in the telephonic reception of telegraphic communication involving currents 20 of definite audio frequency supplied to the telephone receiver.

One of the principal objects of the invention is to secure maximum practicable resonance to input currents of definite audio 25 frequency, and also to provide a construction which is simple and inexpensive to construct, of a rugged character in service, and very sensitive to feeble electrical impulses.

Another important object is to provide a 30 construction whereby the mechanical tune of the reed telephone can be altered at the will of the user.

The invention consists of the various novel 35 features hereof and their co-operative organization including the magnetic system, the vibratory reed, the sound-producing diaphragm and the coupling member between them, all as disclosed and described herein.

The drawing is a perspective view of a 40 modified embodiment of magnet system and reed providing a variability of the mechanical tune of the reed by the user or operator.

The ordinary electromagnetic or Bell type 45 of telephonic receiver does not employ mechanical resonance because it is designed to respond to all audio frequencies involved in speech transmission, and therefore it is not at all adapted for selective work. Also its 50 diaphragm (of magnetic material forming part of the magnetic circuit) is directly operated by the electromagnet, with resulting inefficiency due to the impossibility of asso-

ciating with the magnetic circuit an element having such a shape as a diaphragm in such 55 wise as to secure maximum effect of the input current on the diaphragm. Also the magnetic circuit being adapted to the arrangement of the diaphragm of that type of receiver has not been itself of the most 60 efficient form. In the production of my receiver, I have devised initially a very efficient magnetic circuit and then, in order to most effectively use the same, have resorted to the principle of the reed telephone and 65 have devised a coupling member for the purpose of most effectively controlling the transmission of the energy of the input current, acting upon my efficient magnetic circuit, from the reed to a sound-producing 70 diaphragm arranged in another plane generally more or less parallel to the plane of the magnet system, close to the position of the operator's ear and coupled to the reed. The principle of the reed telephone has been 75 applied to selective work but not in nearly as efficient form as herein, either in respect of the magnet system or of the practical employment of mechanical resonance. In my invention, the relation of the diaphragm 80 system to the reed is such as to enable the reed and diaphragm to vibrate efficiently in resonance with the frequency of the input current without blurring of successive sounds produced by the diaphragm. 85

The above-described magnetic organization, in co-operation with the tuning of the reed and a special coordination of diaphragm and reed to be described, is especially useful 90 in radio telegraphy (as to the very important feature of selectivity) in either of two radio systems in general use as follows.

The first is the spark system where the frequency is used of the order of a thousand 95 sparks per second (audio frequency) as employed with so-called impact or quenched spark transmitters, and where there is set up in the receiver a series of groups of impulses which groups are not widely separated, and are of the same frequency as the 100 transmitting spark-frequency. In this case, the telephone reed may be constructed so as to be tuned to the mean frequency employed; that is, if the frequency ranges from 900 to 1100, the reed will be tuned to 1000. 105

The second system is that of undamped or

continuous wave transmission by various types of transmitters wherein at the receiver the so-called beat system is used (at audio frequency) or other means of converting the 5 continuous wave signal current into an audio frequency signal current (such as the rotary tone condenser of the patent of Proctor, No. 1,211,963 of January 9, 1917), in any of which systems the resultant input current in 10 the circuit of the telephone receiver (coils 10, 11 Fig. 2) is purely sinusoidal and its frequency is under the control of the operator. Said magnetic organization is especially useful for such purposes when it is permitted 15 to take the fullest practicable advantage of receiver resonance by means of the construction, hereinafter described, of the diaphragm system, consisting of the sound-producing diaphragm 3 and the means 20 17 for coupling it with tuned reed 14.

It is of the utmost importance in receiving continuous wave signals in radio to utilize mechanical resonance in the telephone to the greatest degree consistent with the prevention 25 of blurring of signal sounds. This importance is due to the large and rapidly-increasing number of continuous wave transmitters, many of which have approximately the same radio frequency. In this situation, 30 the result (in the lack of a suitable telephone receiver heretofore) has been in the telephone such multiplicity of signal sounds of different pitches as to confuse the operator, this notwithstanding his employment of the 35 best radio tuning means and of his selection at will of an optimum note for the signal desired to be observed. I have found that without the invention hereof, when a tuned reed receiver is constructed so as to take full 40 advantage of resonance, the signal sounds will be blurred, and that when a tuned reed receiver is constructed so that the signal-sounds are not blurred, the utilization of resonance will not be involved to an extent 45 sufficient to exclude undesired signals. The receiver of the invention hereof is one in which the signal sounds are not blurred and also where resonance is taken advantage of to the greatest practicable extent consistent 50 with non-blurring, whereby easy reception is secured with the ability to exclude all undesired signals.

In cases where a feebly-damped mechanical receiving system is employed (thereby 55 using resonance to the fullest extent), not only is an appreciable fraction of a second required for the building-up of the amplitude of mechanical vibration of such system to its maximum value, but an equal time is 60 required for the dying-away of such vibrations after the cessation of the input signal current. Such unrestrained prolongation of signal sound interferes with telegraphic signaling because it tends to obliterate the 65 interval between successive groups of vibra-

tions of the mechanical system which constitute the signals. In other words, the sounds representing the telegraphic dots and dashes will run together or be blurred, in manner as if the signaling were attempted 70 on a harpstring. If, on the other hand, the mechanical system is highly damped, it will lack the advantages of the cumulative effect of resonance and the accompanying advantage of selectivity (i. e., the power to exclude 75 foreign signals of different frequency by means of mechanical resonance), so that the resulting signal note will be weak although clearcut and not blurred.

One of the objects hereof is to provide 80 such construction of the diaphragm system, as to either the diaphragm or its coupling with the reed, or both, as to take fullest possible advantage of resonance without producing blurring, in order to prevent the production of signal notes in a telephone from undesired signals having a radio frequency 85 so nearly like that of the desired signals that radio tuning of the circuits at the receiving station cannot exclude the undesired signals from the receiving circuit.

In any practical form of reed telephone, there is a diaphragm (analogous to a sounding board in a music box) just outside the magnet system and reed for the purpose of translating the vibrations of the reed into sound, the diaphragm being permitted by such location to have sufficient surface area (much greater than the reed) to effect such purpose. The location of the diaphragm 90 also is nearer to the position of the operator's ear than it would be practicable to locate the reed itself. But even with the efficient magnetic system above described, the efficiency of co-operation of a reed tuned to the 95 input current and a diaphragm coupled to the reed is greatly increased when the above-stated object of using resonance to the greatest possible extent without blurring is accomplished; that is, of course, in case of 100 adaptation to use with signals having definite frequency of input current.

In the drawing is shown a form of the invention particularly adapted to damp wave transmission, but also of very great utility 115 in continuous wave reception.

In the drawing is shown a form of reed or vibratory member 14 fixed at both its ends as by screws at F, F to the ends or spaced parts of a U-shaped member M of magnetic 120 material, slightly resilient, which forms part of the circuit of the polarizing magnet which includes also the part 11^a, and the reed 14 and also the laminated short and nearly-closed electromagnet core 4. Magnet 11^a is 125 magnetically associated with core 4 at 12 and with member M at 13. The input circuit is to be wound on core 4.

In the drawing the portion 15 of maximum amplitude of vibration of reed 14 lies in gap 130

8 between ends 6^a and 7 of core 4. Diaphragm 3 and the entire system may be mounted or supported in any desired way, and the diaphragm and reed are coupled in accord with 5 the intermediacy of coupling described fully below. Coupling 17 in this case may comprise two members as shown, connected to the reed symmetrically on opposite sides of core 4 at such points on the reed as determined 10 to produce the results of this invention and joined together at point 19 to a common member connected to a central point on diaphragm 3. Coupling 17 may include resilient portion 17^a (in dotted lines) in any 15 case where the desired intermediacy of coupling is not obtained alone by points of connection to the reed intermediate the portion 15 of maximum amplitude of vibration and its fixed ends F.

20 In the drawing, screw W is threaded at H to engage in adjacent leg member M and has its other end abutting against the side of the opposite leg of M, so that the user may adjust the tension and hence the tune of reed 25 14 mounted on M by forcing the legs more or less apart. The thread at H is preferably fine in order to permit fine adjustments of tuning. This form is especially adapted to use in receiving spark or damped wave transmission 30 wherein the audio frequency at the receiving station is fixed by the transmitting apparatus and not adjusted by the operator as in continuous wave transmission. Thus the operator in this case tunes the reed to 35 the fixed audio frequency instead (as in continuous wave transmission) of adjusting the audio frequency at the receiver to a fixed tune of the reed.

The greatest utility of this form, however, 40 is with continuous wave reception. It is especially useful in reducing and excluding signal sounds which in extreme cases might be produced in the preceding forms by interfering signals of such great intensity as to 45 force vibrations on the tuned reed of my receiver, such forced vibrations being permitted the more readily by reason of the partial damping to avoid blurring of signal sounds. Since the reed can be tuned to any 50 one of a wide range of frequencies at will, the operator may adjust his receiving apparatus to such a beat rate or audio frequency produced by the desired signal as will be as distinct from the beat rate or audio frequency 55 produced by an interfering signal as is possible by selection, as, for example, of beat note alone; thereupon the operator can tune the reed to that beat note of the desired signal, with the result of either preventing the 60 reed from responding at all to the rate of the interfering signal or at least reducing the interfering response to such extent as to insure easy reading of the desired signal, no matter how great the intensity of the interfering signal as it reaches the receiving

station. This operation, of course, involves a method as specified in certain of the claims.

The advantages of the invention in general are as follows, in addition to that above 70 specified as to the magnet system and the method involved in the operation of the form of the drawing. In a receiver which is very efficiently and sensitively organized electromagnetically, there is provided a construction which permits the utmost practicable utilization of the principle of mechanical resonance by virtue of the tuning of the reed to the audio frequency of the input current, and such resonance is permitted to be employed without resulting in blurring of the signal-sounds by virtue of the design of the diaphragm system including diaphragm and coupling co-operatively with the reed as a 75 part of the magnet system, with the result of producing a signal sound which in time duration corresponds with the time duration of the signal input current which itself corresponds with the transmitted signal, thereby preventing the running together or blurring of signal sounds without damping the reed to such an extent as to materially reduce the advantage of resonance, all whereby foreign or undesired signal sounds may 80 be excluded.

By intermediate coupling or damping referred to above is meant such damping that, on the one hand, the reed and diaphragm are not allowed to vibrate in response to an input signal over a period of time covering the 100 interval between the given signal and the next succeeding signal, and, on the other hand, the reed and diaphragm are permitted to vibrate a sufficient length of time in response to a given input signal to take the 105 fullest practicable advantage of the cumulative effect of resonance with the accompanying advantage of selectivity.

It is to be understood that the invention is not limited to the embodiments and features specifically shown and described herein, but that such embodiments and features are subject to changes and modifications without any departure from the spirit of the invention.

I claim:—

1. In a telephone receiver, an electromagnetic, nearly-closed circuit having a gap, a winding for the input current associated with said electromagnetic circuit, a polarizing magnet magnetically connected to said electromagnetic circuit at one end whereby the portions of the electromagnetic circuit on opposite sides of the gap are of the same polarity, the opposite end of said polarizing magnet terminating in a resilient U-shaped member, a vibratable reed secured at its outer portions to the legs of said U-shaped member and having an intermediate portion free to vibrate and located within said gap, 115 120 125 130

- 4
- said reed being of the opposite polarity to that of the electromagnetic circuit, an adjusting screw engaging the legs of said U-shaped member for varying the amount of separation thereof to tension said reed for tuning, and a diaphragm connected to said reed.
2. In a telephone receiver, a nearly-closed electromagnetic core, a winding for the input current associated with said core, a polarizing magnet magnetically connected to said core at one end, the other end of said polarizing magnet terminating in a U-shaped member having its legs adjacent the gap between the ends of the nearly-closed electromagnet core and on opposite sides of said gap; a vibratable reed secured at its outer portions to the legs of said U-shaped member and having an intermediate portion free to vibrate and located within said gap; an adjusting screw engaging the legs of said U-shaped member for varying the amount of separation thereof to tension said reed for tuning, and a diaphragm connected to said reed.
3. In a telephone receiver, a magnetic circuit constructed with a gap in one end and having the other end terminating in a U-shaped member having its legs adjacent said gap and on opposite sides thereof; a vibratable reed having its outer portions secured to the legs of said U-shaped member and having an intermediate portion located in said gap and free to vibrate therein; and an adjusting screw engaging the legs of the U-shaped member.
4. In a telephone receiver, an electromagnetic core having a gap in one end, a magnetic U-shaped member magnetically linked with said core and having its legs located adjacent said gap and on opposite sides thereof; a winding on said core; a vibratable reed having its outer portions secured to the legs of said U-shaped member and having an intermediate portion located in said gap and free to vibrate therein; and an adjusting screw engaging the legs of the U-shaped member.
5. In a telephone receiver, an open magnetic circuit one end of which comprises a nearly-closed laminated electromagnet core and the other end of which comprises a vibratable reed extending through the gap between the ends of the nearly-closed electromagnet core; an intermediate portion of the magnetic circuit comprising a U-shaped part having its legs located alongside said core-gap and having said reed secured to its legs; and an adjusting screw engaging the legs of the U-shaped member.
6. In a telephone receiver, the combination with a magnet system and a vibratable reed, of a diaphragm and means for coupling the diaphragm and reed; of means for adjusting the reed which comprises a U-shaped end of the magnetic circuit of the magnet system on the legs of which the reed is secured; and an adjusting screw engaging said legs.
